UNITED STATES PATENT OFFICE.

LUDWELL H. GILMER, OF TACONY, PENNSYLVANIA, ASSIGNOR TO L. H. GILMER CO. OF LA., INC., A CORPORATION OF LOUISIANA.

LOOM.

Application filed July 20, 1927. Serial No. 207,176.

As is well known, the usual shuttle motion in looms is operated by means of straps either of leather or of web material which, inherently, are materially affected by stretching, 5 due to varying conditions of humidity and wear. When these straps stretch, naturally they become loose and impart a considerable jerk, to the shuttle, as lost motion is being taken up. This stretching of the straps very 10 materially limits the speed of the shuttle motion, besides which this jerking motion is the direct cause of the breaking of the teeth in the batten rack.

One of the objects of my invention resides 15 in a positively driven element, positively connecting the shuttle motion lever and a batten with a common prime mover.

Another object of my invention is to provide a rigid connection between the shuttle 20 motion lever, and operating parts therefor, which is in constant relation to the loom frame and held against swinging with the batten.

Another object of my invention is to provide 25 a shuttle motion lever having a bearing at its upper end on which the batten is slidably mounted.

With these objects in view my invention 30 consists of the parts and combination of parts as will be hereinafter more fully set forth.

In the drawings:

Figure 1 is an end elevation of the loom with my invention embodied, parts being 35 shown in section, and parts shown in dotted lines.

Figure 2 is a front detail elevation of one end of the loom, parts being omitted.

Figure 3 is a detail elevation of part of 40 the loom.

Figures 4 and 5 show the invention embodied in a double deck loom.

As will be seen from description herein, due to the rigid elements connecting the 45 shuttle motion lever and the batten by rigid element to the power, all operating parts work in constant relation to the loom frame and do not in any way swing with the batten.

The frame of the machine is provided with 50 suitable bearings 15 in which is mounted a shaft 14 on which shaft the shuttle motion lever is journaled at its lower end. The shuttle motion lever, according to my invention, as illustrated herein, is composed of 55 two arms 13 which are connected together by

means of the pin 13^a, which pin is keyed by means of the key 13^b. The upper ends 13^c of the lever 13 are spread out to form yoke ends for the lever, which yoke ends are connected by means of the shaft 18 suitably secured thereto. 60

A suitable casting 12 is revolvably mounted on the pin 13^a to which is secured one end of the rod 11, the other end of the rod being connected to a casting 11^a, which casting in turn 65 is revolvably mounted on the pin 9 secured to the disc 10, which disc is mounted on the shaft 8.

The means for operating the shuttle motion lever starts with an eccentrically mounted 70 gear 1 on the crank shaft 2 of the loom. This gear into the elliptical gear 3 running at half the speed of the gear 1. The gear 3 through the shaft 4 drives a pair of mitre gears 5, thence through the shaft 6 to another pair of mitre gears 7, and thence through shaft 8 to the disc 10, which through its crank pin 9 and the rod 11 connects positively and directly to the shuttle motion lever. 75

Referring now to the forked ends 13^c of the 80 shuttle motion lever, it will be seen that I have mounted thereon a cross head 20 which is provided with an elongated vertically disposed slot 29 in which the rectangular rod 18 is positioned, the head 20 being slidably 85 mounted on the rod 18. This head 20 is slidably mounted on the rods 21, which rods extend at right angles to the rod 18 of the shuttle motion lever as more clearly shown in Figure 2. These rods 21 are connected 90 to the batten 22 by means of the brackets 23 and 24. The bracket 24 is dropped down at the end of the batten to permit of ready removal of the rack bar 25 for repairs. To remove the rack bar 25 the nut 26 is removed, 95

whereupon the bracket 27, which is attached by screws, and the like, 28, to the rack bar 25, and the rack bar are free to be removed from the loom out from the end of the batten. 100

The slide or cross-head 20, as above related, 105 is provided with an elongated slot 29 in which the rod 18 is free to reciprocate to slide to accommodate the swinging motion of the shuttle motion lever 13. The batten 22, carried by the cross-head 20, in the process of weaving, swings backward and forward in the loom between the forked ends of the shuttle motion lever 13, as clearly shown in Figure 1. In weaving the batten 22 swings forward and backward, the same as it does in 110

any loom; in the backward position the warps being open to offer a passage for the shuttle, the batten then coming forward to beat up the filling. By means of the slot 29 in the cross-head 20 and the bearings in the upper ends of the shuttle motion lever, the shuttle motion lever is available to operate in any position of the batten, being always positively driven and under control of the operating mechanism so that no bumpers are required. In this connection it will be recalled that bumpers are required for the shuttle motion levers in the looms as now practiced. 30 is a supporting bracket.

15 The cross-head 20 is connected to a crank 33 on the shaft 2 by means of the rod or pitman 31, whereby the cross-head 20 and the batten are positively driven by rigid member, such as the bar or pitman 31.

20 One great advantage of this shuttle motion is that due to its constant positive control and easy motion in starting and stopping the shuttles, all rack breakage due to the shock, which is daily experience in the looms now in use, has been done away with.

In usual commercial practice the shuttle motion has been largely the limiting element in speed at which looms can be practically operated. With this new shuttle motion the limit 30 of speed, as far as the particular part of the mechanism is concerned, has been entirely eliminated, besides which another very desirable result of my invention is that I am enabled to materially reduce the noise in the loom room.

35 As has been stated, the main object of this shuttle motion is to have the driving or operating part of the mechanism working in constant relation to the main frame of the loom and not in any way affected by the motions of the batten.

The inventive thought herein taught may be carried out in a double deck loom as shown in Figures 4 and 5.

45 In Figure 4 the rods C correspond with the rods 21 in the other figures. D are the batten rack bars. These batten rack bars are connected by the cross-head or slide E, which slides on the rods C. The cross-head E is 50 provided with an elongated slot F, which corresponds with the elongated slot 29 in the other figures of the drawing. The operation in this embodiment has been described in connection with Figures 1, 2 and 3.

55 In the embodiment shown in Figure 5 the batten bars are designated by the reference

letter D, while the cross-head is designated by the reference letter G. In this instance the cross-head G comprises two members which are connected together by a bar K, on 60 which is mounted the knuckle L, said knuckle being free to slide vertically on the bar K. This knuckle L is provided with an aperture M through which a rod corresponding to the rod 18 (Figure 1) is adapted to move.

These embodiments shown in Figures 4 and 5 with the description just given will be sufficient for those skilled in the art to understand the same.

What I claim is:

1. In a loom, a shuttle motion lever terminating in two spaced arms at its upper end, a cross head constituting a batten bearing extending between the upper ends of said arms and a batten on said cross head.

2. In a loom, a batten, and a shuttle motion lever having an elongated transversely disposed batten bearing at its upper end.

3. In a loom, a shuttle motion lever having an elongated bearing at its upper end, and a batten slidably mounted on said bearing.

4. In a loom, a shuttle motion lever having an elongated bearing at its upper end, a batten slidably mounted on said bearing, and positive rigid connections between said lever and said bearing and the power transmitting elements of the loom.

5. In a loom, a shuttle motion lever pivotally mounted at its lower end to the frame of the loom, and terminating in a fork at its upper end, an elongated transversely disposed batten bearing in said forked end, a carrying member slidably mounted on said bearing, and capable of movement independent of the lever, in one direction, a batten secured to said carrying member, and a rigid operating bar extending between the batten and a prime mover, and a rigid bar extending between the said lever and its prime mover.

6. In a loom, a shuttle motion lever terminating at its upper end in a fork, a bearing in said fork, a carrying member, movable on said bearing transversely of the lever, a joint between the upper end of the lever and said member permitting a relative vertical movement between the lever and member, a batten secured to said member, a rigid operating bar secured to the batten, and a rigid operating bar secured to said lever.

In testimony whereof I affix my signature,

LUDWELL H. GILMER.
